UNITED STATES PATENT OFFICE.

THOMAS McCORMICK, OF SOMERVILLE, MASSACHUSETTS.

PNEUMATIC CONCRETE STEEL CAR-BUMPER.

No. 821,524.

Specification of Letters Patent.

Patented May 22, 1906.

Application filed December 11, 1905. Serial No. 291,353.

To all whom it may concern:

Be it known that I, THOMAS McCORMICK, a citizen of the United States, residing at Somerville, in the county of Middlesex and 5 State of Massachusetts, have invented a new and useful Improvement in Pneumatic Concrete Steel Car-Bumpers, of which the following is a specification.

This invention relates to means for stopping railway rolling-stock at the ends of railway tracks and sidings and particularly to a bumper for this purpose which shall be air-cushioned and rigidly anchored.

The object of this invention is to provide a car-bumper or end-rail obstruction of such design and structure that a car or locomotive coming into contact with it will be stopped with the least possible concussion and damage to the car and the bumper, thus 20 assuring an efficient obstruction.

Another object is to provide a reliable and durable bumper for the purpose just specified.

The invention therefore consists in the 25 structure hereinafter described and claimed and which is illustrated in the accompanying drawings, wherein—

Figure 1 represents the improved bumper in plan, Fig. 2 a vertical longitudinal central section thereof, and Fig. 3 an end elevation.

The bumper is in the main made up of a mass of concrete, in which a buffer is mounted. This buffer may be variously constructed, but by preference it has a cylinder 4, cast or otherwise formed from iron or steel, and within this cylinder is located a plunger 5, having a protruding portion of less diameter than the portion within the cylinder, thereby 35 forming a shoulder, which rests against a ring or collar 6, removably secured to the outer end of the cylinder. For the sake of compactness the plunger is hollow, as shown, and is provided with a shoulder or ledge within this hollow or recess, between which and the rear end of the cylinder extends a spiral spring 7, guided by the rod 9, which is preferably screwed into the rear end of the cylinder and extends into the plunger slightly beyond 40 the ledge 8.

The mass of concrete for anchoring the buffer may be formed and secured in place in various ways, but preferably in the manner illustrated, wherein a couple of piles 10 are 45 driven into the ground and protrude suffi-

ciently above the track-rails 11 to permit a piece of rail 12 to be bolted securely thereto while resting firmly on the track-rails. The forward end of the mass of concrete is formed over these two piles. A couple of other piles, 60 as 13, are driven into the ground to the rear of the first piles and protrude sufficiently above the ground to enter well into the rear end of the mass of concrete. These latter piles assist in preventing the rear end of the 65 mass of concrete from being tipped into the ground, while the forward pair of piles assist in preventing the forward end of the mass of concrete from being lifted. The track-rails also are preferably upturned at their ends 70 to assist in preventing longitudinal displacement of the mass of concrete, and to further insure against this longitudinal displacement and the tipping down of the rear end of the mass of concrete a piece of rail 14 may be laid 75 across the track-rails. Reinforcing-rods, as 15, extend longitudinally of the concrete mass near its upper surface and other reinforcing-rods, as 16, extend over the rods 15 and downwardly to the track-rails, through perforations in which the ends thereof are passed and upwardly turned, as indicated in Fig. 3. It is just beneath this network of reinforcing-rods that the buffer is located, and to provide a more extended surface to receive the 80 thrust of the cylinder a number of pieces of rail are placed transversely of the mass of concrete against the end of the cylinder, as indicated at 17. As a precaution against the withdrawal of the cylinder from the mass of 85 concrete should it become at all loosened in its seat one or more ridges or projections may be formed upon the exterior of the cylinder or a collar or band, as indicated at 18, may be secured to the cylinder in any suitable 90 manner.

To provide against a sudden rebound of the plunger and to give a more cushioned effect thereto when struck by a car, a vent from the cylinder is formed, as indicated at 100 19 in Fig. 3. This vent also provides for ingress of air to permit a ready return of the plunger in response to the pressure of the spring 7.

Obviously many changes in details and in 105 the formation and combination of parts may be made without departing from the spirit of the invention.

The invention claimed is—

1. A car-bumper consisting in the combi- 110

nation of a mass of artificial stone anchored at the end of a railway-track and a buffer anchored therein.

2. A car-bumper consisting in the combination of a mass of concrete anchored at the end of a railway-track and a pneumatic buffer anchored therein.

3. A car-bumper consisting in the combination of a mass of concrete anchored on the rails of a railway and a buffer mounted in said mass.

4. A car-bumper consisting in the combination of a mass of concrete anchored to the ground by piles and a buffer mounted in said mass.

5. The combination with the rails of a railway-track, of a mass of concrete formed upon said rails, metal rods secured to said rails and embedded in the concrete and a buffer mounted in the mass of concrete.

6. The combination with the rails of a railway-track, of a mass of concrete formed upon said rails, metal rods secured to said rails and embedded in the concrete, piles secured in the ground and having their upper ends anchored in the concrete.

7. A car-bumper consisting in the combination of a mass of concrete anchored at the end of a railway-track, a pneumatic cylinder anchored therein, a plunger located in said cylinder and a spring for protruding the end of the plunger beyond the cylinder.

8. The combination with the rails of a railway-track, of a mass of concrete formed upon said rails, substantially as specified.

9. The combination with the rails of a railway-track, of a mass of concrete formed upon

said rails, and anchored to the ground by piles, substantially as specified.

10. The combination with the rails of a railway-track, of a mass of concrete formed upon said rails, and anchored to the ground by piles, of a buffer supported by steel rods embedded in the concrete, substantially as specified.

11. The combination with the rails of a railway-track, of a mass of concrete formed upon said rails, and anchored to the ground by piles, of a buffer supported by steel rods embedded in the concrete and reinforced by turned rail ends and cross-pieces, substantially as specified.

12. The combination with the rails of a railway-track, of a mass of concrete formed upon said rails, and anchored to the ground by piles, of a pneumatic buffer composed of a pneumatic cylinder and a plunger or ram located within said cylinder, an escape cock or valve located at the rear of said cylinder, of a spring for protruding the end of the plunger beyond the edge of the cylinder, said pneumatic cylinder being supported by steel rods embedded in the concrete, reinforced by turned-rail ends and cross-pieces, all being anchored in the concrete, substantially as specified.

In testimony whereof I have signed my name to this specification in the presence of two subscribing witnesses,

THOMAS McCORMICK.
